UNITED STATES PATENT OFFICE.

HERBERT C. HEADSTREAM, OF RIB LAKE, WISCONSIN.

DOUBLE-ACTING AIR PUMP.

Application filed April 16, 1925. Serial No. 23,495.

This invention relates to a pump, and particularly a double-acting pump adapted to pump and compress fluids, the device being particularly designed for compressing air.

5 It is an object of this invention to provide a simple and efficient double-acting pump comprising two sets of cylinders, one set of which is valve equipped and the other of which is not valve-equipped.

10 It is a further object of the invention to provide such a pump, as set forth in the preceding paragraph, comprising two pairs of cylinders, the cylinders of each pair being axially alined and having pistons therein 15 connected by a common piston rod, said piston rods, in turn, being connected to an operating means.

It is another object of the invention to provide a pump comprising spaced chambers 20 in which the fluid is compressed, which chambers are connected by a suitable valve-controlled conduit, one of said chambers having an outlet conduit connected thereto, said pump comprising two sets of cylinders, one 25 set of which communicates with one chamber and the other set of which communicates with the other chamber.

It is a still further object of the invention to provide such a pump as set forth comprising 30 a simple and efficient frame conveniently arranged for carrying all of said parts.

These and other objects and advantages of the invention will be fully set forth in the following description made in connection 35 with the accompanying drawings in which like reference characters refer to the same parts throughout the different views, and in which—

Fig. 1 is a central vertical section through 40 the pump;

Fig. 2 is a horizontal section taken on the line 2—2 of Fig. 1;

Fig. 3 is a horizontal section taken on the line 3—3 of Fig. 1;

Fig. 4 is a horizontal section taken on the line 4—4 of Fig. 1;

Fig. 5 is a horizontal section taken on the line 5—5 of Fig. 1, said sections being taken as indicated by the arrows; and

50 Fig. 6 is a view in vertical section illustrating the structure of valve used.

Referring to the drawings, a pump is shown comprising a frame formed of a lower portion 7, intermediate portion 8, an upper portion 9, and a top portion or cover 10. The portion 7 is of general elliptical shape,

as shown in Figs. 4 and 5 and has formed therein cylinders 11 and 12, said cylinders being disposed at opposite sides of said frame portion and transversely alined or 60 having their top and bottom portions, respectively at the same level. The cylinders 11 and 12 have inlet valves 13 at their lower ends, and while these valves may be of any suitable type permitting air to move into 65 the cylinders but preventing air leaving the same the construction is substantially shown in Fig. 6. In said figure, the valve is shown comprising a valve 13^a adapted to contact the seat 13^b to close the valve but being movable from said seat against the spring 13^c, a one-way check valve being thus provided. The space in the frame section between the cylinders 11 and 12 forms a storage chamber for air and said space communicates with 70 the bottom of cylinders 11 and 12 through the outlet valves 14, said valves 14 permitting the exit of air from said cylinders but preventing air entering the same. The frame section 7 has a circular flange 7^a at its upper end contacting a similar and equal size flange 8^a at the bottom of the central section 8, said flanges being tightly pulled together by headed and nutted bolts 15. The section 8 has a circular flange 8^b at its upper end 75 which, in turn, is bolted to a similar and equal sized flange 9^a at the lower end of the upper section 9 by similar headed and nutted bolts 15. The upper section 9 is substantially cylindrical in shape, as shown in Fig. 90 2, and also has at opposite sides thereof cylinders 16 and 17. The space between the cylinders 16 and 17 also forms a storage space for air, said space having the bottom or diaphragm 9^b and said space communicating with the upper ends of cylinders 16 and 17. The cylinders 16 and 17 preferably are 95 of larger diameter than the cylinders 11 and 12.

It will be noted that the lower ends of 100 cylinders 16 and 17 are open and that the upper ends of the cylinders 11 and 12 are open. The cylinder 16 is axially alined with the cylinder 11 and the cylinder 17 is axially alined with the cylinder 12. All of 105 said cylinders are equipped with pistons, the cylinders 11 and 12 having the pistons 18 and 19, respectively, therein while the cylinders 16 and 17 have pistons 20 and 22, respectively, therein. The pistons 19 and 110 22 are connected by a common piston rod 23. While the pistons 18 and 20 are, like-

wise, connected by a common piston rod 24, which rods pass through the central frame portion 8. The piston rods 23 and 24 are adapted to be operated by a common operating member and while they may be variously formed, in the embodiment of the invention illustrated, said piston rods are formed as oppositely directed racks and a gear 25 is provided, the teeth of which mesh with the teeth of said racks. The frame portion 8 has a central rib or member 8^c extending thereacross having spaced intermediate portions provided with oppositely extending central bosses 8^d which are bored to receive a shaft comprising a headed stud 26 journaled therein and held in place by having one end threaded and provided with a suitable nut. Said stud has a central portion of angular shape in cross section on which the gear 25 is mounted. The gear 25 and the flattened portions of piston rod 23 and 24 forming the rack move through the member 8^c which thus forms a guiding means therefor. The shaft or stud 26 is adapted to be oscillated and while this may be done by any suitable means, in the embodiment of the invention illustrated, a lever 27 is shown as connected to stud 26 by a suitable set screw 27^a, which lever projects through an opening in one side of the frame portion 8. The chamber in the frame portion 7 and the chamber in the upper portion 9 are connected by a pipe or conduit 28 having disposed therein a valve 29 and an outlet pipe 30 communicating with pipe 28 through a suitable T connection is provided also equipped with a valve 31. The top section 10 is of semi-spherical formation having a circular flange bolted to an upper flange 9^c on the section 9 by headed and nutted bolts 32, said top section 10 forming the top of the chamber in section 9. A gasket (not shown) preferably will be provided between section 10 and flange 9^c to provide an air-tight joint.

When the pump is to be operated for compressing fluid, the valve 29 will be opened and valve 31 closed. Lever 27 will then be oscillated by any suitable means and piston rods 23 and 24 will then be reciprocated in opposite directions. As the pistons 18 and 19 are raised, air is drawn into the cylinders 11 or 12, respectively, through the inlet valves 13 and then when pistons 18 and 19 are depressed, this air is compressed and forced through the outlet valves 14 into the chamber between cylinders 11 and 12. Air is thus compressed and forced into said chamber and the pressure in said chamber equalizes through the pipe 28 with the upper chamber between cylinders 16 and 17. During this operation of the pump it will be noted that the pistons 20 and 22 form guide means for the pistons 18 and 19, respectively, and for the piston rods 24 and

23. Said pistons and rods are thus kept accurately in proper alinement. There will be no additional power required to raise the piston 20 or 22 as the pressure in the chamber communicating with said pistons will tend to force one piston down at the same pressure required to lift the other piston. After a sufficient pressure of air has been attained in the storage chambers the valve 29 may be closed and the compressed air supplied to the desired apparatus through the pipe 30 by opening valve 31. The air can be supplied from both chambers, if desired, by allowing valve 29 to remain open or the pressure can be raised in the lower chamber after some of the air has been used by opening valve 29.

From the above description it is seen that applicant has provided a simple, compact and efficient structure of pump or compressor. The pistons 18 and 19 are effectively operated by a common operative member 25 and the pump is quite rapid in securing the desired pressure of air. The parts of the device are comparatively few and simple and easily made and such parts are quite easily assembled. By having the chambers between cylinders 11 and 12 and at the upper end of cylinders 16 and 17, the structure is greatly simplified and the chambers and cylinders are provided with a minimum of frame structure. By having the cylinders 16 and 17 opening directly into the chamber at the upper end thereof, conduits connecting this storage space with the cylinders are eliminated, as is also the necessity of cylinder heads. The arrangement of pairs of cylinders in alinement, with the common parts operating them also results in a machine functioning and accomplishing the desired result with a very small number of parts. A very compact and efficient machine is thus provided.

It will, of course, be understood, that various changes may be made in the form, details, arrangement and proportions of the parts without departing from the scope of applicant's invention which, generally stated, consists in a device capable of carrying out the object above set forth and in the novel parts and combinations of parts disclosed and set forth in the appended claims.

What is claimed is:

1. A double-acting pump for compressing fluids having in combination, a pair of parallel cylinders, a chamber into which said cylinders discharge through valve controlled passages, inlet valves for said cylinders, a pair of parallel cylinders spaced from and respectively axially alined with said first mentioned cylinders, a chamber communicating with the ends of said last mentioned cylinders, pistons in all of said cylinders, a pair of piston rods respectively connecting the pistons in said axially alined cylinders,

- a movable member operatively connected to said piston rods for moving the same simultaneously in opposite directions and a conduit connecting said chambers.
- 5 2. The structure set forth in claim 1, a valve in said conduit for opening and closing the same, and a valve-controlled conduit communicating with said first mentioned chamber.
- 10 3. A double-acting pump for fluids having in combination, a frame, a chamber at the bottom thereof, a pair of cylinders having their upper and lower ends, respectively in the same horizontal plane at each side of said chamber, said cylinders having discharge ports at their lower ends opening into said chamber, inlet ports in said cylinders at their lower ends, the upper ends of said cylinders being open, said frame having a chamber at its upper end, a pair of parallel cylinders at the sides of said last mentioned chamber having open upper ends at the same level communicating with said last mentioned chamber and having open lower ends at the same level, said last mentioned cylinders each alining axially with one of said first mentioned cylinders, pistons in all of said cylinders, a connecting rod connecting the pistons in each pair of axially alined cylinders, a valve controlled conduit connecting said chambers, an operating shaft journaled in said frame between said chambers and a member on said shaft engaging both of said connecting rods to move the same in opposite directions, and means for oscillating said shaft.
4. A double-acting pump for compressing fluids having in combination, a pair of parallel cylinders, a chamber into which said cylinders discharge through valve controlled passages, inlet valves for said cylinders, a pair of parallel cylinders spaced from and respectively axially alined with said first mentioned cylinders, a chamber communicating with the ends of said last mentioned cylinders, pistons in all of said cylinders, a pair of piston rods respectively connecting the pistons in said axially alined cylinders, a frame carrying all of said cylinders including a member disposed substantially centrally between said pairs of parallel cylinders and having a rectangular slot therein, a pair of oppositely facing racks in the ends of said slot, a gear disposed in said slot meshing with both racks, a shaft carrying said gear journaled in said member, and means for turning said shaft and gear.
5. A double-acting pump for fluids having in combination, a pair of parallel cylinders having inlet and outlet valves at their lower ends and being open at their upper ends, a chamber into which said cylinders discharge, a pair of parallel cylinders having open upper and lower ends spaced from said first mentioned cylinders, each of said last mentioned cylinders being axially alined with one of said first mentioned cylinders, a closed chamber with which the upper ends of said last mentioned cylinders communicate, pistons in all of said cylinders, a piston rod connecting the pistons in each pair of axially alined cylinders, a conduit connecting said chambers, a valve-controlled outlet conduit for said first mentioned chamber, and means for reciprocating said piston rods simultaneously in opposite directions.
6. A double-acting pump having in combination, a frame comprising a lower section having parallel cylinders at opposite sides thereof, inlet valves at the lower ends of said cylinders, respectively, outlet valves at the lower ends of said cylinders, said frame forming a chamber between said cylinders with which said outlet valves communicate, the upper ends of said cylinders being open, said frame comprising an upper portion having at opposite sides thereof parallel cylinders, each of which is axially alined with one of said first mentioned cylinders, said last mentioned cylinders being open at both ends and said upper portion of said frame forming a chamber with which the upper ends of said cylinders communicate, said frame having an intermediate portion bolted respectively to said lower and upper portions, a shaft journaled in said intermediate portion, a gear mounted on said shaft, pistons in all of said cylinders, a piston rod connecting the pistons in each pair of axially alined cylinders, said piston rods passing through said central frame portion and being formed with rack teeth on their adjacent sides, said teeth meshing with the teeth of said gear, means for oscillating said gear, and a conduit connecting said chambers.

In testimony whereof I affix my signature.
HERBERT C. HEADSTREAM.
